(57) **CLAIM**

I claim an ornamental design for footwear, as shown and described.

DESCRIPTION

FIG. 1 is a left side view of footwear, showing my design;

FIG. 2 is a right side view thereof;

FIG. 3 is a bottom view thereof;

FIG. 4 is a top view thereof;

FIG. 5 is a front view thereof; and,

FIG. 6 is a back view thereof.

The large broken lines indicate stitching. The small dashed lines indicate unclaimed environment and forms no part of the claimed design.
